UNITED STATES PATENT OFFICE.

WALTER S. COE, OF BROOKLYN, NEW YORK, ASSIGNOR TO MERGENTHALER LINOTYPE COMPANY, A CORPORATION OF NEW YORK.

SLUG-CASTING MACHINE.

1,304,660.

Specification of Letters Patent. Patented May 27, 1919.

Application filed April 12, 1917. Serial No. 161,401.

To all whom it may concern:

Be it known that I, WALTER S. COE, a citizen of the United States, residing at Brooklyn, in the county of Kings and State 5 of New York, have invented certain new and useful Improvements in Slug-Casting Machines, of which the following is a specification, reference being had therein to the accompanying drawing.

10 My invention has reference to slug casting machines, such as linotype machines of the general organization represented in Letters Patent of the United States No. 436,532 to O. Mergenthaler, wherein a slug or linotype is cast in a slotted mold against a composed line of matrices which produce the type characters thereon. In these machines, the molds are usually mounted in a vertical intermittently rotating disk or wheel which 15 presents the selected mold in a horizontal position for casting and thereafter carries it around to a vertical position in front of an ejector blade which pushes the cast slug therefrom.

20 25 My present invention is directed to an improved mounting of the mold disk, as will be fully described in the detailed description to follow.

In the accompanying drawing, I have 30 shown my invention merely in preferred form and by way of example and as applied to a linotype machine, and obviously many changes and variations therein and in its mode of application may be made without departure from its spirit. Generally speaking, I desire it to be understood that I do not limit myself to any specific form or embodiment, except in so far as such limitations are specified in the claims.

35 40 Referring to the drawing:—

Figure 1 is a detached perspective view of the so-called "mold slide" upon which the disk is mounted; and

Fig. 2 is a plan view of the assembled 45 parts showing in section the mold disk and its improved mounting.

As usual the mold disk A, equipped with one or more molds A¹, is mounted for rotation upon the arm or support B¹ projecting laterally from the mold slide B, which 50 is arranged to be reciprocated forwardly and backwardly in the machine frame by its operating cam B². The disk A is intermittently rotated by the driving pinion A² 55 in such manner that during casting the se-

lected mold is presented in a horizontal position and after casting carried around to a vertical position, as shown in Fig. 2, where it registers with a pair of trimming knives D¹ between which the slug is ejected from the mold by an ejector blade carried by the operating slide C. As is well known, the reciprocation of the mold slide B is timed so as to move the disk rearwardly when it is to be rotated to carry the selected mold from casting to ejecting position, or vice versa, and to move the disk forwardly when in either of such positions, in one case to insure the close contact of the mold with the composed matrix line, and in the other, to locate the mold in immediate proximity to the trimming knives. The mold disk is provided with a pair of dowel-pins A³ which, when it is moved forwardly, engage in corresponding sockets A⁴ secured rigidly to the vise frame, such engagement effecting and maintaining the proper registration of the mold with the cooperating devices. At its free end the arm B¹ is provided with the "back" knife D¹, which trims the base of the slug while in the mold. The parts so far described, except as hereinafter pointed out, are or may be of any approved construction.

As before stated, the present invention is directed to means of improved construction 85 for mounting the disk upon the laterally projecting arm or support B¹. In the embodiment illustrated, the disk A is rotatably mounted upon a large hollow bearing sleeve or boss E detachably connected to the arm or support B¹ by means of a solid cylindrical stud or bolt F passing loosely through an open socket member B³ formed on the support and through a central opening E¹ of the boss, the stud being provided at its 90 front end with a clamping nut or collar F¹ screw-threaded to a reduced portion thereof and bearing against the front face of the boss to retain it thereon. By unscrewing the nut F¹, the boss E may be instantly 95 slipped off the stud F or the latter itself removed. When the boss is clamped in position by the nut F¹, it is seated within and flatly up against the bottom face of a recess B⁴ which is cut into the arm or 100 support B¹ to receive it.

At its rear face the boss E is provided with an annular flange E² interposed between the support B¹ and the rear face of the mold disk and which is of greater thick- 105 110

ness than the depth of the recess B^4 . The flange E^2 thus serves not only as a spacer or washer to hold the mold disk away from the support B^1 , but also as a guide for the 5 disk during its floating or vertical movement with respect to the boss, it being noted in this connection that the diameter of the boss is slightly less than that of the opening or bearing in the disk to permit of such 10 floating action.

The disk is retained in place by a cap plate G detachably secured by screws G^1 to the boss E and formed with a central opening G^2 to fit over the clamping nut F^1 . The 15 plate G in addition to its retaining function serves in coöperation with the flange E^2 to guide the mold disk in its floating movements.

It will be understood, of course, that all 20 the parts are properly machined to insure their functioning in the required manner. It is also noted that, if desired, the hollow boss E may be used for the circulation of a cooling medium, its interior cavity being 25 in the form of a closed annular chamber surrounding the opening E^1 and through which the cooling medium may be freely circulated.

My improved construction presents many 30 advantages over those of the prior art, not only in respect to the cost of manufacture and the greater efficiency and accuracy in the operation of the machine, but also in respect to the convenience of attaching the 35 mold disk and the other parts to and detaching them from the mold slide when desired. The construction is also such as to permit the utilization of old parts which have heretofore been unavailable for use in 40 the more modern machines. Such advantages and others will be apparent to those skilled in the art.

Having thus described my invention, its 45 construction and mode of operation, what I claim and desire to secure by Letters Patent of the United States, is as follows:

1. In a slug casting machine, the combination of a rotatable mold disk, a support formed with an open socket member, a stationary bearing sleeve or boss upon which the mold disk is rotatably mounted and provided with a central opening arranged in endwise alinement with the open socket member, and a sustaining stud or bolt separate 55 from the boss and passing freely through the

socket member and freely through the opening of the boss and provided at one end with a nut or collar screw-threaded thereon to clamp and hold the parts detachably together. 60

2. In a slug casting machine, the combination of a rotatable mold disk, a support provided with a sustaining stud, a bearing sleeve or boss upon which the mold disk is mounted and formed with a central opening through which the sustaining stud passes, a 65 clamping nut screwed on the free end of the stud and bearing against the front face of the bearing sleeve or boss, and a cap plate detachably secured to the boss and bearing against the front face of the mold disk and formed with a central opening to clear the clamping nut. 70

3. In a slug casting machine, the combination of a rotatable mold disk, a support, and a bearing sleeve or boss fixed to the support and upon which the mold disk is mounted, the said boss being provided at its rear face with an annular flange forming a washer between the mold disk and the support. 75

4. In a linotype machine, the combination of a mold slide having a laterally projecting arm or support formed in its front face with a recess, a bearing sleeve or boss secured to the support within the recess and 85 formed at its rear face with an annular flange of greater thickness than the depth of the recess, and a mold disk rotatably mounted upon the bearing sleeve or boss. 80

5. In a linotype machine, the combination 90 of the mold slide B having the laterally projecting arm or support B^1 provided with the open socket member B^3 and formed in its front face with the recess B^4 , the bearing sleeve or boss E located in the recess B^4 and 95 formed with the rear flange E^2 and the central opening E^1 , the stud or bolt F passing through the socket member B^3 and the opening E^1 of the boss E , the clamping nut or collar F^1 screwed on the stud F and bearing against the front face of the bearing sleeve or boss E , the mold disk A mounted 100 upon the bearing sleeve or boss, and the retaining plate or cap G detachably secured to the boss E and bearing against the front 105 face of the mold disk, substantially as shown and described.

In testimony whereof, I have affixed my signature.

WALTER S. COE.
